JACKET FOR WATER-COOLED TUBES

William C. Schmitt, Hackensack, N. J., assignor
to Federal Telephone and Radio Corporation,
New York, N. Y., a corporation of Delaware

Application October 6, 1951, Serial No. 250,051

1 Claim. (Cl. 257—250)

1

This invention relates to heat exchangers used in combination with electron discharge devices of the high power type, and more particularly to connecting assemblies therefor.

In the operation of high power electron discharge devices of the type used in transmitting equipment, it is well known that the power dissipated by the anode and other electrodes in the form of heat, must be absorbed by a fluid coolant, either air or water, to prevent the discharge device from attaining an excessively hot state which might distort or melt the electrodes thereof. It is well known that if forced liquid cooling is utilized in combination with an electron discharge device designed for the purpose, a higher power output is obtainable from the device than would be obtainable if forced air cooling were utilized due to the more efficient thermal conductivity of liquid as compared with a gas, and affords efficient plate heat dissipation. It is the practice to provide an anode structure which projects through the usual glass envelope of the device and to cause a high velocity flow of water around such anode. In the prior art, a separate cooling jacket was provided which was adapted to encompass the anode. Separate jackets create problems of fluid-tight joints between the jacket and the discharge device, and difficulty of removal upon replacement of a spent discharge device. The prior art devices were also deficient in that a considerable head-room was required in the transmitter cubicle, the head-room being equal to at least the length of the anode within the cooling jacket, such space normally being unused and therefore unnecessarily wasted and requiring large transmitter cubicles. Another deficiency of the prior art devices resulted from the lime deposits which formed within the cooling jackets and which rendered the fluid-tight joint between the anode and the jacket difficult to unseal, due to the cement-like quality of such deposits.

An object of this invention is to provide an electron discharge device of the type requiring fluid cooling with a cooling jacket permanently associated therewith with single means for easily and rapidly mounting same in fluid-tight relation with a coolant source.

Another object of the invention is to provide an electron discharge device of the type having an external anode and requiring fluid cooling, said device having a cooling jacket permanently affixed to said anode in fluid-tight relation, said jacket having inlet and outlet ports leading into said container, fluid-tight means for connecting

2

said container to a source of a fluid coolant and single fastening means for rendering said ports fluid tight.

According to a feature of the present invention there is provided in combination an electrical discharge device of the type having an external anode, a cooling container surrounding said anode and permanently affixed thereto, said container having inlet and outlet ports, means for mounting said device and said container in operating position, said means comprising a mounting member having apertures in register with said ports, fluid-tight means disposed between said container and said mounting member, and single means associated with said mounting means for locking said container in fluid-tight relation therewith.

The above-mentioned and other features and objects of this invention and the manner of attaining them will become more apparent and the invention itself will be best understood, by reference to the following description of an embodiment of the invention taken in conjunction with the accompanying drawings, wherein:

Fig. 1 is a sectional elevational view of a portion of an electron discharge device and its permanently attached cooling jacket;

Fig. 2 is a sectional view of the mounting base with which the electron discharge device and jacket cooperate;

Fig. 3 is a top plan view of the mounting base;

Fig. 4 is a sectional view of the electron discharge device and its jacket mounted in operating position upon the mounting base; and

Fig. 5 is a cross-sectional side view of a portion of the mounting base of the jacket shown in Fig. 1.

Referring to Fig. 1, there is shown an electron discharge device of the high-power dissipation class which requires liquid cooling, comprising an enclosing vessel having an insulating portion 1, preferably of glass and having an extended cup-shaped conductive portion 2 which forms the external portion of the anode of the device. The anode 2 is sealed to the vessel at 3 in a conventional manner thus rendering the enclosing vessel air-tight. There is further shown a co-operating cooling jacket 4 permanently affixed to said anode and adapted to substantially surround same. The jacket comprises a base portion 5 and an outer member 4A spaced coaxially from said anode and attached at one end thereof at 6 to said base portion by means of a low-melting point fusible material, such, for instance, as soft solder. The outer member 4A has an in-

wardly curved portion generally indicated at 4B. The jacket further comprises an inner cylindrical portion 4C which has substantially the same configuration as the anode, and which is adapted to be connected to said anode by means of a low-melting point fusible material, such for instance, as soft solder. Both the inner and the outer portions are mutually attached at 7 by means of a high-melting point fusible material. There is further provided an intermediate member 8 spaced coaxially from said inner and outer portions and connected at 9 to the extended portion 10 of the base 5. The inner portion 4C is also attached to extended portion 10 at 9A. The connections at 9 and 9A may be made by any suitable means such for instance, as by threaded joints (not shown) which would enable easy assembly and later demounting of the jacket walls from the base portion 5. The intermediate member 8 defines two separate chambers, the first chamber 11 together with the inner member 4C and another chamber 12 with the outer member 4A. Both of said chambers are mutually in connection at 13. The inner chamber 11 is provided with a fluid inlet port 14 which port extends exteriorly of the base at 15. The outer chamber 12 is provided with a fluid outlet port which port extends through the base 5 at 16. Thus, if a fluid is introduced through the inlet port 14 the inner chamber 11 will become flooded and the fluid will overflow over the top of the intermediate member 8 into the outer chamber 12 as indicated by the arrow and thence through the outlet port 16. The base portion has a central aligning post 17 axially projecting outward therefrom. The post 17 has a partially tapered recess 18 extending radially thereinto, which recess is provided for a purpose which will be explained below.

In Fig. 2, there is shown in section a cooperating mounting plate 19, which is in the nature of a socket for the discharge device and its cooling jacket. The plate 19 has a pair of apertures 20 which register with the inlet pipe 16 and the outlet port 15, respectively, of the base 5 of the jacket. There is also provided a third aperture 21 to register with the aligning post 17. A transverse threaded aperture 22 is provided in plate 19 through which a screw 23 having a tapered end (Fig. 3) is adapted to travel.

It will be apparent that the tapered end of screw 23 will seat into the tapered recess 18 of the aligning post 17 and will tend to draw the base portions 5 close to the mounting plate 19. In order to provide a water-tight seal, the apertures 20 in the base plate are provided with gasket retaining grooves 24 which are coaxial with the apertures 20 and are cut into the upper surface of the mounting plate 19. A pair of resilient gaskets 25 (only one of which is shown in Fig. 2) are adapted to seat within the retaining grooves and extend part distance above the surface of plate 19. It will be seen that when the discharge device and its jacket are placed into the mounting plate and the aligning post is drawn down by the tapered screw, the two gaskets will be compressed by axial pressure exerted thereupon and will thereby form a fluid-tight seal between apertures 15, and the corresponding apertures 20. The bottom portions of the apertures 20 are threaded to take suitable fluid conducting pipes 27 (Fig. 4) leading from a source not shown and to a fluid cooling system (not shown). Under ordinary plumbing procedure such pipes may be provided with wicking or

pipe-joint compound to provide a fluid-tight seal with the base plate.

Disposed on the underside of the mounting plate 19 are a pair of small threaded apertures 28 (Fig. 3) adapted to take mounting screws and which screws are adapted to mount the mounting plate onto a suitable frame member 29 (Fig. 4) which may be insulated from the transmitter frame proper by conventional stand-off insulators (not shown).

When a tube fails or is required to be replaced, the tapered screw 23 is withdrawn from the recess 18 in the aligning post 17 and thereupon the entire assembly consisting of the electron discharge device and its attached jacket may be withdrawn by merely lifting the same out of the mounting plate a distance equal to the axial length of the aligning post 17. It will be appreciated that only one element need be unscrewed, that is, the tapered screw 23, to permit the ready withdrawal of the discharge device and jacket assembly and that upon the re-insertion of a new tube, the tightening of the tapered screw will reseal the inlet and outlet ports by means of the axial pressure exerted upon gaskets 25. Thus, in the event of tube failure, a replacement can be made in the space of a few minutes as opposed to the ponderous technique which was followed heretofore in unfastening water jackets having threaded compression joints surrounding the tube anodes which were very often encrusted with scale and lime deposited over a period of time by the circulating fluid.

Fig. 5 shows a cross-sectional side view of the aligning post 17 of the jacket base in Fig. 1 and presents a clear idea of the manner in which tightening of the screw 23 of the mounting base 19 in recess 18 draws the discharge device and its jacket down into fluid-tight relation with the mounting plate.

The anode 2 is not subjected to high temperatures in the application thereto of the jacket assembly, due to the use of low-melting point fusible material, thus preventing distortion of the anode. In the event of failure of the discharge device, the cooling jacket may be salvaged by unsoldering the outer member 4A at 8; unsoldering the anode from the inner portion 4C; and unfastening the extended portion 10 of the base 5. The two chambers 11 and 12 could thus be cleaned of all scale and deposit and the jacket re-conditioned for re-installation on a new discharge device by reversing the removal process detailed above.

If desired, a set of cooling fins (not shown) 55 may be applied to the anode instead of a cooling jacket, thus providing an air-cooled discharge device.

While the invention has been disclosed in a particular embodiment, various modifications may be made in the structure and assembly without departing from the scope of the invention as defined in the appended claim.

What is claimed is:

In a mounting arrangement for the fluid cooling jacket of an electron tube on a mounting plate, said tube cooling jacket having fluid inlet and outlet ports extending through the base portion thereof and said mounting plate having two apertures extending therethrough and in register with said inlet and outlet ports, with gaskets sealing each of said ports to its apertures; means for mounting the jacket in sealing position on the mounting plate comprising a central aligning post coaxially projecting outwardly from the base

portion of said jacket, said post having a tapered recess radially disposed along the length thereof, said mounting plate having a corresponding aperture through which said aligning post projects, a tapered screw key extending transversely through said mounting plate, said key being aligned with and adapted to fit with its end into the tapered recess in said post and by action of the tapered key on the tapered recess to force the jacket down towards the mounting plate and to press said gaskets into fluid tight relation between said base and portion and said mounting plate.
